Inventor:

UNITED STATES PATENT OFFICE.

OLOF NORDIN, OF SÖDERTELJE, SWEDEN.

RAIL-JOINT CONNECTION.

SPECIFICATION forming part of Letters Patent No. 699,224, dated May 6, 1902.

Application filed October 8, 1901. Serial No. 77,490. (No model.)

To all whom it may concern:

Be it known that I, OLOF NORDIN, a subject of the King of Sweden and Norway, residing at Södertelje, in the Kingdom of Sweden, have 5 invented certain new and useful Improvements in Rail-Joint Connections; and I do hereby declare the following to be a full, clear, and exact description of the invention, such as will enable others skilled in the art to which 10 it appertains to make and use the same, reference being had to the accompanying drawings, and to figures of reference marked thereon, which form a part of this specification.

The present invention relates to rail-joints, 15 its object being to prevent shocks as the rolling-stock passes over the joint and to make the rail-joint as durable as possible.

The invention is shown in the accompanying drawings, in Figure 1 in a side view and 20 a longitudinal section on line *a b* of Fig. 2, which latter shows a top view of the joint. Figs. 3 and 4 are cross-sections, respectively, on lines *c d* and *e f* of Fig. 1 viewed from the left.

25 The device is characterized by the two rails 1, 2 to be joined together being placed with their ends sufficiently apart to leave a greater intermediate space than ordinarily and locating in this space between the rail ends on 30 each side the angle-shaped fish-plates 3, 4, having a form corresponding to the rail-head 7 and held together by means of a bolt 6. The fish-plates 3, 4 bear against each other by means of the faces 5 along a vertical plane 35 extending longitudinally. The head 7 is cut away wedge-shaped at each rail end. The portions cut away are replaced by the fish-plates 3, 4, which thus at the rail-heads 7 obtain lateral faces 8, diverging from the longitudinal direction of the rail. At the faces 8 40 are the intermediate spaces 15, required to provide for the variations in length of the rails. The points 9 of the wedge-ends of the rail-heads 7 are rounded off, so as to give them about the same width as the web 10. The 45 extremities 11 of the fish-plates at the sides of the rail-heads are cut off perpendicularly to the longitudinal direction of the rail, so that no sharp points are left at said extremi-

ties. The lower portion of the fish-plates 3, 4 is embraced by upwardly-projecting edges 12 of a bottom plate 13, which keeps the joint rigid. Fish-bolts 14 are carried through the rail ends and fish-plates 3, 4 for holding said parts together. By means of this device, consequently, shocks are excluded when the rolling-stock is passing over the joint. This rail-joint, moreover, is more durable than any other. The device also offers a great advantage in being readily applicable to the rails 60 and joints previously in use.

I claim—

1. In a rail-joint, the combination of rails having their heads cut away wedge-shaped at the ends, two fish-plates 3, 4 entering between 65 the rail ends, which are located apart, and replacing the portions of the rail-heads cut away, said fish-plates 3, 4 being held together by a fish-bolt 6 carried through the fish-plates 3, 4 at the space between the rail ends, and 70 here having faces 5 bearing against each other along a longitudinal plane, and a bottom plate 13 having upwardly-projecting lateral edges 12 embracing the lower portions of the fish-plates 3, 4, for the purpose set forth.

2. In a rail-joint, the combination of rails having their heads cut away wedge-shaped at the ends, two fish-plates 3, 4 entering between the rail ends, which are located apart, and replacing the portions of the rail-heads cut 80 away, said fish-plates 3, 4 being held together by a fish-bolt 6 carried through the fish-plates 3, 4 at the space between the rail ends, and here having faces 5 bearing against each other along a longitudinal plane, and a bottom plate 85 13 having upwardly-projecting lateral edges 12 embracing the lower portions of the fish-plates 3, 4 and rounded points 9 on the wedged ends of the rails, for the purpose set forth.

3. In a rail-joint, the combination of rails 90 having their heads cut away wedge-shaped at the ends, two fish-plates 3, 4 entering between the rail ends, which are located apart, and replacing the portions of the rail-heads cut 95 away, said fish-plates 3, 4 being held together by a fish-bolt 6 carried through the fish-plates 3, 4 at the space between the rail ends, and here having faces 5 bearing against each other

along a longitudinal plane, and a bottom plate 13 having upwardly-projecting lateral edges 12 embracing the lower portions of the fish-plates 3, 4, and fish-bolts 14 for holding together the fish-plates 3, 4 and rail ends, for the purpose set forth.

In testimony that I claim the foregoing as

my invention I have signed my name in presence of two subscribing witnesses.

OLOF NORDIN.
